UNITED STATES PATENT OFFICE.

THOMAS C. SPELLING, OF NEW YORK, N. Y.

STOPPER.

1,118,244.

Specification of Letters Patent.

Patented Nov. 24, 1914.

Application filed September 11, 1913. Serial No. 789,368.

To all whom it may concern:

Be it known that I, THOMAS C. SPELLING, citizen of the United States, residing at New York, in the county of New York and 5 State of New York, have invented certain new and useful Improvements in Stoppers, of which the following is a specification, reference being had therein to the accompanying drawing.

10 This invention relates to improvements in stoppers made of cork, or other soft or yieldable substance, and has for its object the provision of a cork which may be readily extracted, unimpaired, to enable repeated use of the same, and to eliminate the ordinary and necessary use of a cork screw or the like with its attending liability to tear or break, and consequently destroy the cork as an effective sealing agent in subsequent use.

15 My invention comprehends the provision of a stopper of the character designated with an improved means accompanying the same, and forming part thereof, adapted to project without a bottle mouth in position to be readily grasped in withdrawing the cork intact from the bottle.

20 Broadly, the invention embraces a pull member formed separately of the cork, and 30 of sufficiently strong and durable material to enable the performance of its expected functions, and provided with improved anchoring means to insure extraction of the cork therewith, said anchoring means including barbed prongs deflected laterally into the substance of the cork and firmly embedded therein to resist the pulling strains exerted during the withdrawing action of the stopper.

25 More specifically, the invention comprises the combination with a cork body, of means adapted to be seated therewithin, and bearing a barbed prong or prongs located with reference to said means to facilitate an insertion of the same into a suitable slotted portion or recess formed in the cork, and said means and prongs being so related as to cause lateral deflection and penetration of the prongs into the substance of the cork 35 upon a partial withdrawing movement of said means, and which penetration will be sufficient to secure the cork, means, and barbs together against further relative

movement, so that additional pulling force will result in extracting the cork and its 55 associated parts intact and capable of renewed service as an efficient stopper.

To facilitate the imparting of a full and complete understanding of the invention, I will illustrate herein the preferred embodiment of the same, together with other embodiments thereof, and the details in the arrangement and combination of parts will be appreciated from a reading of the specific description hereinafter contained in connection with the accompanying drawings forming a part hereof, and wherein such embodiments are illustrated.

In the drawings, Figure 1 is a vertical sectional view through a cork showing my 70 improvements as originally inserted therein, Fig. 2 is a similar view showing the pull means in their anchored relation to the cork, Fig. 3 is a vertical section of the device as shown in Fig. 2 taken at right 75 angles to the section of the latter view. Fig. 4 is a transverse sectional view of Fig. 2. Fig. 5 is an elevation of a modified form of device, Fig. 6 is a detail perspective view of an implement employed in connection with the proper seating of the pull member in the cork; Fig. 7 shows a modified wire retaining means, Fig. 8 is a sectional view through a guiding shell facilitating the introduction of still another form of 85 my pull member; Fig. 9 is a similar view with the pull member in place in the cork, the shell being drawn outwardly over the projecting prongs of the same, Fig. 10 is a transverse sectional view, Fig. 11 is a detail perspective view, and Fig. 12 is an edge view of the stem portion *g* of the wire anchoring means of Figs. 8 and 9.

Referring more specifically to the drawings, wherein like reference characters 95 designate corresponding parts in the several views, A represents a cork of usual formation and conventional shape, although it might be of any shape desired, or other substance of a soft or yieldable nature, as previously stated, the cork being provided with a slit or incision B opening from the top of the cork as at *b* and terminating in the lower portion of the cork as at *b'*, so that said incision does not pass through the substance of the cork but is confined entirely 100 105

therewithin to the end that the sealing characteristic of the cork is not lessened by the incision.

C represents a carrier comprising a small 5 slab or plate, conveniently of metal, wood, or other suitable substance, the same being, generally speaking, oblong in shape, and of a sufficient thickness to provide a pair of grooves c, in one face of the plate extending 10 from the upper end of the same, in a converging relation, downwardly to near the lower end of the plate where they communicate as at c' with recesses D formed at the opposite edges of the plate by inclining said 15 edges inwardly as at d above right angle shoulder portions E, similarly projected in opposite directions to constitute the bottoms of the recesses, and operating as hereinafter set forth, the extreme bottom edge of the 20 plate being tapered or rounded as at F to facilitate the insertion thereof, as will also presently appear.

G is a pull member formed either entirely 25 of a single piece of wire, as shown, or partly of a suitable cord and partly of wire, as will be obvious, the intermediate or looped portion g of which is of substantial fullness to enable the passage of a finger therethrough, and the depending opposite runs or branches 30 g' of the wire constituting the stem being seated in the grooves c in the plate. The portions g' of the wire, to which I have just alluded, have offset terminal portions H at the lower ends of the same adapted to project out of the lower ends of the grooves c 35 and through the recesses D into the substance of the cork A, the terminal portions being sharpened at their points and provided at said points with suitable barbs, or 40 roughened or grooved members h'. The carrier plate C is also provided with transverse apertures J through which a wire K may be wound on the plate, as best shown in Fig. 3, with the terminals of such wire 45 projecting outwardly from the lowermost aperture, and pointed and barbed as at h.

By reference to Fig. 4, a means for clamping the wire in the grooves will be seen as 50 constituted by offsetting or pressing inwardly the flanged portions c² of the metal plate C constituting the outer wall of the grooves c, this deflection of the flanges serving to bind the wires in the grooves, as is 55 apparent. In some instances, it will not be necessary to bind the wires in the grooves, and in such cases the plate or slab may be formed of wood or similar material and a thin piece of paper or the like L (Fig. 7) 60 may be laid across the wires and pasted in place to prevent the escape of the wires from the grooves c.

From the foregoing description, the method of inserting and securing the pull to the cork may be readily followed to wit: 65 the incision B having been made in the cork,

the pull with the prongs H occupying the position shown in Fig. 1, that is, along the inclined walls d with their points projecting slightly outwardly and downwardly beyond the edge of the plate C, may be forced 70 into the interior of the cork, the tapered lower end F facilitating this operation, until the lower end of the plate engages the base of the opening formed by the incision. In this inserting operation, the prongs will 75 preferably be drawn through the substance of the cork, the latter yielding or cutting sufficiently for that purpose. Following this step (illustrated in Fig. 1) the pull g is engaged by the finger or equivalent means 80 and the plate C raised until its upper edge is flush, or nearly so, with the upper surface of the cork, in which raising action of the plate the prongs H will be forced outwardly into approximately the position 85 shown in Fig. 2, where the pointed ends thereof have penetrated a substantial distance into the substance of the cork, and the barbs h' will overcome any withdrawing tendency thereof incident to the further 90 pulling movement of the loop g, and in this connection the shoulders E will prevent straightening out of the prongs in line with the grooves c, thereby facilitating the maintenance of the penetrated relation of the 95 prongs to the substance of the cork. To assist in this lateral deflection of the prongs H the wire G is weakened as at N (the junction of the edge recess D and groove c), which will permit the bending of the wire at 100 this point and until obstructed by the shoulders E as previously set forth. This same raising of the plate C in the cork also causes the prongs h to similarly embed themselves in the substance of the cork at right angles 105 to the embedding of the prongs H. In some cases, as in connection with relatively large corks, or where relatively heavy wire is employed, or in fact in every instance, the seating of the anchor in its final position in the 110 cork body may be facilitated by an implement such as illustrated in Fig. 6, the same being merely an inverted U-shaped strip of metal N' having notched legs n adapted to 115 be slipped over the edge of the plate C (see dotted lines Fig. 1), and held in place while the plate is pulled upwardly so that the prongs H will be positively forced to ride outwardly through the notched portions n, rather than rely entirely on the prongs feeling their own way, so to speak, into the substance of the cork, although the latter operation will probably in the main be relied upon.

In Fig. 5, I have illustrated a modified 125 form of device in connection with which the plate C is entirely eliminated. Here, the wire forms the loop O, the depending branches o (or stem) of which are formed with return bends o' pointed and barbed as at o'. 130

A strip of paper, for example, P holds the return bend portions o' in parallel relation to the stem during the insertion of the device in a slitted cork, and would simply tear 5 away when the device of this figure is partially elevated in the cork to deflect the prongs outwardly into the substance of the cork and upon the same principle underlying the insertion and operation of the device 10 of the other figures of the drawings previously discussed. The stem portions of the wire, in this instance, are fastened together against spreading by a drop of solder or the like, o^3 .

15 In Figs. 8, 9, 10 and 11 I have illustrated still another embodiment of my invention wherein the pull part of the cork is formed of wire looped as at Q and having the depending branches or stem portions q secured 20 together (preferably by paper) as at R to fasten the same against undue separation in the initial inserting movements, and to provide a shoulder r . The ends of the wire are barbed as at q' and normally spread outwardly as at S.

T is a tube in the nature of a thin rectangular cage or guide shell adapted to be inserted in the slitted cork to facilitate the introduction of the pull member of the cork 25 into the latter, the narrow edge walls t of the shell being provided with downwardly flaring outlet openings U, through which the pointed ends q' of the pull wire will enter and be guided outwardly by the end portions 30 of downwardly turned separated, but closely associated, shelves or flanges q'' of the shell (Fig. 8) and which normally constitute a bottom to close the space within the tube below the openings U, as approximately indicated in Fig. 10. The shelves flaring in a downward direction to some extent as they approach each other, help the prongs in finding entrance to the openings U, as will be apparent. To force the pull wire downwardly and laterally with sufficient force to 45 adequately penetrate the cork body, a needle-like tool V, having an offset split grip or jaw v at its lower end may be engaged with the stem portions of the wire above the abutment or shoulder r constituted by reducing the wire, as shown, the lower portions of the wire in this instance being preferably flat (Fig. 12). By pressing the tool downwardly, of course the wire is also carried downwardly, the tie paper split therefrom, and the branches of the pull wire caused to deflect outwardly or laterally as 50 previously stated. To enable withdrawal of the tube or shell, and repeated use thereof, the edge walls of the shell below the openings U are slitted as at W to permit the embedded prongs passing therethrough, after they have similarly passed through the shell portion thereabove and between the shelves 55 q'' , the latter yielding sufficiently for that

purpose, and all that is necessary is to withdraw the shell under sufficient force to spread the said shelves and sides X of the shell apart, the latter being yieldable for that purpose, while normally constituting a 70 relatively sharp edge Y to assist in inserting the shell in the cork, as will be apparent.

The tool V may be manipulated by hand, but it is the intention of applicant to operate the same by machinery, wherein the 75 tube will be held in a fixed position with reference to the corks supported in a suitable carrying means, and with this understanding we state that Z is a spring bulge or catch formed with or carried by the shank of the 80 needle-like tool V adapted to yield with the shank of the tool in an inward direction when the same is being inserted into the shell past a shoulder z at the top of the shell, but to project outwardly below said 85 shoulder when the tool is raised in its withdrawing movement, so that such engagement will enable the tool to pull the shell out of the cork, when the substance of the cork may close up the space previously occupied 90 by the shell and around the wire pull, the wire being the only element intended to remain as a permanent part of the cork in this instance, as distinguished from the form of Figs. 1, 2 and 3, where the carrier 95 and wire both remain permanently in the cork.

I will not claim herein those specific branches of the present invention embraced within the method, and in the embodiment 100 of the first three figures of the drawing inasmuch as these, in keeping with the examiner's requirement to that end, more properly constitute subject matter for divisional application.

Having thus described the invention, what is claimed is:—

1. A stopper comprising a cork body, a pull therefor carried permanently thereby as a portion of the stopper, said pull comprising a shank extending lengthwise of said body and to the top thereof to constitute an engaging part, and an integral extension of said shank permanently offset therefrom to constitute a fixed anchoring portion penetrating and embedded directly in the cork substance in a plane at an angle to the shank, the end of the offset portion remote from its juncture with the shank being provided with a cork engaging projection to prevent withdrawal thereof through the cork substance, substantially as and for the purpose described.

2. Means for inserting wire pull means in corks comprising a shell of a relative size 125 to be substantially completely embedded in the cork and having longitudinal and lateral passages for the wire, and guiding means for bodily bending the wire to constitute integral shank and offset portions with- 130

in the cork substance to permanently fix the pull member in said substance and prevent removal thereof, said shell being open at the top of the pull to permit a finger-engaging portion of the wire to project therethrough above the upper surface of the cork.

3. The combination with a pull for stoppers of the character described comprising oppositely disposed prongs associated with an outwardly projecting finger engaging portion, of separate means removable independently of the pull adapted to be inserted in the cork to facilitate the positioning of said prongs, substantially as described.

15 4. Means for inserting wire pull members in corks, comprising a shell having suitable openings for the wire, means for causing lateral deflection of the wire into the cork body, and means permitting withdrawal of 20 the shell over the wire, substantially as described.

5. Means for inserting wire pull members in corks, comprising a shell having lateral outlet openings for the wire and separable portions 25 therebelow permitting the wire to pass through the shell in withdrawing the latter.

6. Means for inserting wire pull members in corks, comprising a shell having lateral outlet openings for the wire and separable 30 portions therebelow permitting the wire to pass through the shell when withdrawing the latter, in combination with a tool for forcing the wire through the shell and into the cork, substantially as described.

35 7. Means for inserting wire pull members in corks, comprising a shell having lateral outlet openings for the wire and separable portions therebelow permitting the wire to pass through the shell when withdrawing 40 the latter, in combination with means for forcing the wire through the shell and into the cork, said tool being formed to engage the shell to assist in withdrawing the same from the cork.

45 8. A pull member for corks, comprising a finger engaging portion, and separated prongs carried thereby adapted to be embedded laterally of said engaging portion into the body of the cork, and a destructible 50 tie member for the shanks of the prongs, substantially as and for the purpose described.

55 9. A pull member for corks comprising a finger engaging portion, and separated barbed prongs carried thereby adapted to be embedded laterally of said engaging portion into the body of the cork, and a de-

structible tie member for the shanks of the prongs, substantially as and for the purpose described.

10. The combination with a pull for stoppers of the character described comprising a prong associated with an outwardly projecting finger engaging portion, of means adapted to be inserted in the cork to cause 65 permanent interlocking of the prong with the substance of the cork, substantially as described.

11. The combination with a pull for stoppers of the character described comprising 70 a prong associated with an outwardly projecting finger engaging portion, of separate means removable independently of the pull adapted to be inserted in the cork to facilitate the positioning of the prong, substantially as described.

12. The combination with a pull for stoppers of the character described comprising a prong associated with an upwardly projecting finger engaging portion, of means 80 adapted to be inserted in the cork to effect positioning of the prong when said means moves in one direction only, substantially as described.

13. The combination with a pull for stoppers of the character described comprising a prong associated with an outwardly projecting finger engaging portion, of means adapted to be inserted in the cork to effect 90 positioning of the prong when said means moves in one direction but to free itself relative to the prong when moved in another direction.

14. In combination with a cork stopper, a pull therefor, and an insert coöoperating 95 with the pull comprising a shell through which a portion of the pull is passed, said shell being approximately completely embedded within the cork and having open lower and upper portions, the pull having 100 an under projecting portion passing through the lower opening of the shell and into the substance of the cork and also having a finger engaging portion projecting out of the upper opening of the shell adapted to 105 be pulled when extracting the cork, substantially as described.

In testimony whereof I affix my signature in presence of two witnesses.

THOMAS C. SPELLING.
